UNITED STATES PATENT OFFICE

2,416,371

METALLIC MEMBER FOR JOINING WOODEN ELEMENTS IN DEMOUNTABLE INTERLOCKING RELATION

Walter Allan Bockius, Glenview, Ill.

Application November 3, 1944, Serial No. 561,814

3 Claims. (Cl. 20—92)

1

This invention relates to joints, and in particular to improved means for joining wooden members.

The preferred embodiment of my invention herein shown and described is particularly designed for joining wooden structural members in furniture making and cabinet work, although it is obvious that the invention may be applied to timber joining and heavier types of construction.

It is an object of my invention to provide a joint of simple construction, but which is comparatively strong, and also a joint which is demountable.

A further object is to provide a metal interlocking member which may be secured to a wooden structural member, or the like, and which is adapted to receive in interlocking relationship, the ends of additional wooden structural members in order to make an easily assembled joint.

Other objects, features and advantages will appear as the description proceeds.

With reference now to the drawings,

Fig. 1 is a perspective view of a joint formed according to this invention;

Fig. 2 is a top sectional view of the joint shown in Fig. 1, the view being taken along line 2—2 of Fig. 4;

Fig. 3 is a sectional view of the interlocking member, taken along line 3—3 of Fig. 4;

Fig. 4 is an elevation of the joint shown in Fig. 1, the elevation being partly in section;

Fig. 5 is a perspective view of the interlocking member;

Fig. 6 is a plan view of a modified form of interlocking member;

Fig. 7 is an elevation of the interlocking member shown in Fig. 6; and

Fig. 8 shows shelving embodying my invention.

With reference now to Fig. 1, an upright structural member 10 is shown, to which are secured longitudinal horizontal members 11 and 12, and a transverse horizontal member 13. The joint between these members is effected by means of an interlocking member designated generally by the reference 14. The interlocking member is preferably formed from sheet steel and comprises a box-like structure having two partitions 15 and 16 therein which divide the interlocking member into three compartments designated by the reference numerals 17, 18 and 19.

The side walls 20 and 21, and the bottom 22 of the interlocking member are folded from a sheet of metal, and are provided with slots 23 into which lugs 24 of the partitions 15 and 16 extend. These lugs are bent over and serve to

2

reinforce the walls of the interlocking member. The partitions 15 and 16 are also provided with downwardly extending lugs 25 which are received in suitable slots in the bottom member and are bent over.

It will be seen from Fig. 5 that the compartments 17, 18 and 19 are all open at the top, and also at a side. The side openings are formed by inwardly extending flanges designated by the reference numerals 26, 27 and 28, respectively, for each of the three compartments.

The end portions of the horizontal members 11, 12 and 13 are provided with grooves, as indicated by the reference numeral 29 with respect to member 11. The end portions of the various horizontal members fit into the several compartments 17, 18 and 19, the flanges 26, 27 and 28 being received in suitable grooves in the horizontal members so as to interlock the parts.

20 The interlocking member 14 is secured to the upright member 10 by means of screws 30, as shown in Figs. 2 and 4.

A lip 22, to be received in a horizontal slot in the upright 10, is also provided to make the assembly more secure against wearing.

25 It will be seen that the type of joint herein described is very secure for the reason that each of the horizontal members is securely interlocked with respect to the others, and with respect to the upright member 10.

A modified form of this invention is shown in Figs. 6 and 7, wherein one of the end compartments, designated by the reference numeral 19' is provided with an opening in the side wall 20, rather than with an end opening of the type shown in Fig. 5. Another difference is that the end compartment 19 is not provided with a bottom, the purpose of this construction being to receive a board 31, or a piece of plywood which is adapted to form a closure or a wall for the structure which is formed by the structural members 10, 11, 12 and 13, or their counterparts.

As an example of one use for a joint of this type, it can be stated that in the construction of shelving as shown in Fig. 8, the interlocking members 14 would be secured to a number of uprights 10, and the shelves 33 would be supported both longitudinally and transversely by members corresponding to the horizontal members 11, 12 and 13. At either end of the shelving, an interlocking member 14', such as that shown in Figs. 6 and 7, would be used, for the reason that this would hold in place an end wall formed by a board 31.

50 It is obvious, however, that the joint herein shown and described is capable of numerous other

applications. Furthermore the structural members need not necessarily be of wood.

Although I have shown and described only preferred embodiments of my invention, it is obvious that various modifications and changes may be made therein. The foregoing description and drawings are deemed to be illustrative only, and my invention is to be limited only by the appended claims.

I claim:

1. In a joint for wooden structural members, an interlocking device comprising a U-shaped member providing side walls and a bottom wall, and a plurality of interior partitions for dividing the interior of said box-like structure into separate compartments and a slot in an outer wall of each of said compartments, the slot in one of said compartments extending through the bottom wall, and being bounded on one side by a portion of one of said side walls which is bent forwardly to provide an end wall substantially equal in length to the width of said compartment, and being bounded on the other side by a portion of the opposite side wall which is bent backwardly.

2. An interlocking member for providing a structural connection between an upright member and a plurality of horizontally disposed members, comprising a sheet steel member bent into a U-shape to provide a bottom and side walls, apertures provided in said side walls, vertically disposed partitions in said U-shaped member and provided with lugs which extend through said apertures and interlock therewith, said vertically disposed partitions dividing said U-shaped member into three compartments, one of said side walls being cut away to provide an opening for the middle compartment which is narrower than the length dimension of said compartment, and the ends of said side walls being bent inwardly to provide openings into the end compartments which are narrower than the width dimension of said compartments, whereby slotted horizontally disposed members may be positioned with their ends in each of said three compartments, the portions of the side walls of said U-shaped member which bound said openings extending into the slots in said horizontally disposed members.

3. An interlocking member for providing a structural connection between an upright member and a plurality of horizontally disposed members, comprising a sheet steel member bent into a U-shape to provide a bottom and side walls, apertures provided in said side walls, vertically disposed partitions in said U-shaped member and provided with lugs which extend through said apertures and interlock therewith, said vertically disposed partitions dividing said U-shaped member into three compartments, one of said side walls being cut away to provide an opening for the middle compartment which is narrower than the length dimension of said compartment, and the ends of said side walls being bent inwardly to provide openings into the end compartments which are narrower than the width dimension of said compartments, whereby slotted horizontally disposed members may be positioned with their ends in each of said three compartments, the portions of the side walls of said U-shaped member which bound said openings extending into the slots in said horizontally disposed members, and the side wall of said U-shaped member which is opposite to that side wall having an opening provided therein, being provided with a transversely disposed lip which is adapted to fit into a correspondingly disposed slot in said upright member.

WALTER ALLAN BOCKIUS.
